UNITED STATES PATENT OFFICE

137,088

DESIGN FOR A LAMP

Jonathan I. Houck, Pottstown, Pa.

Application March 11, 1943, Serial No. 109,722

Term of patent 14 years

To all whom it may concern:

Be it known that I, Jonathan I. Houck, a citizen of the United States of America, residing at Pottstown, in the county of Montgomery and State of Pennsylvania, have invented a new, original, and ornamental Design for Lamps, of which the following is a specification, reference being had to the accompanying drawing, forming a part thereof.

The rear and side not shown are substantially the same as the front and side illustrated.

I claim:

The ornamental design for a lamp, as shown and described.

JONATHAN I. HOUCK.
